UNITED STATES PATENT OFFICE.

ALLAN R. HODGES, OF MEMPHIS, TENNESSEE, ASSIGNOR OF ONE-HALF TO CYRUS A. McALLISTER, OF MEMPHIS, TENNESSEE.

RADIAL STAY FOR LOCOMOTIVE-BOILERS.

1,249,958.

Specification of Letters Patent. Patented Dec. 11, 1917.

Application filed February 23, 1917. Serial No. 150,515.

To all whom it may concern:

Be it known that I, ALLAN R. HODGES, a citizen of the United States, residing at Memphis, in the county of Shelby and State 5 of Tennessee, have invented new and useful Improvements in Radial Stays for Locomotive-Boilers, of which the following is a specification.

This invention relates to an improvement 10 in radial stays for locomotive boilers employed more particularly for the purpose of bracing relatively to one another the fire-box shell and the outer shell.

In such boilers, the fire-box shell becomes 15 highly heated while the outer shell is still relatively cold, with the result that the fire-box shell expands rapidly during an interval when the outer shell is expanding comparatively slowly. On the other hand, the 20 outer shell is the first to cool and cooling rapidly contracts rapidly, while the fire-box shell is cooling, and, hence, contracting, relatively slowly. In those constructions 25 wherein radial stays of rod or bolt form are employed to brace and connect the two shells, the stay rods or bolts are of flexible construction, *i. e.*, they are constructed to have a certain measure of loose play in the direction of their length in order to avoid 30 the otherwise destructive effects which the contraction and expansion of the shells would have each on the other.

Flexible stay rods or bolts of the constructions ordinarily employed are open to 35 the following principal objections: First they require considerable work of difficult character for their fitting; second, they embody connections of somewhat elaborate and expensive character for their attachment 40 to the shells, which connections are a source of more or less continual trouble by reason of becoming loose or sprung and causing leakage, and, in the case of the fire-box shell, of deteriorating rapidly under 45 intense heat due to low water conditions, with the result that the fire-box is inadequately stayed and becomes ruptured or subject to collapse; and third, on being stripped in connection with the renewal of 50 either of the shells, they are practically destroyed or at least rendered unfit for further use, in consequence of which, when stripped, they are discarded or "scrapped".

The principal object of the present invention is to provide a radial stay which

will overcome the above disadvantages. Stated in positive terms, the principal objects of the invention are to provide radial stays whose sections or parts may be fitted and organized relatively to one another and 60 to the shells with ease and facility even where the work is being conducted in the narrowest or least accessible parts of the steam space between the shells, may be connected to the shells in such manner that 65 their connections with the shells will not be liable to springing or looseness, and, in the case of the fire-box shell, will materially resist the destructive effects of intense heat under low water conditions; and by virtue 70 of their construction and means of connection to the shells may be efficiently re-used after being stripped incident to the renewal of either of the shells.

Further objects of the invention are to 75 provide a radial stay of exceedingly simple, inexpensive and durable construction; in which, without the introduction of any element of structural complication, effective provision may be made for transverse as 80 well as longitudinal flexibility; in which, any degree of flexibility necessary in an existing situation may be conveniently provided for; and in which the resisting pull is along a straight axis common to both sections of the stay and to the engaging elements of the flexible joint of said stay sections.

With the above objects in view, the invention consists in certain novel features in 90 involving the structure of the stay and its relation to the shells.

An embodiment of the invention is illustrated in the accompanying drawings, 95 wherein:—

Fig. 1 is a partial cross-sectional view showing the arrangement of the improved radial stays between the fire-box shell and the outer shell.

Fig. 2 is a detail sectional view showing 100 the connection of the stays to the fire-box shell.

Fig. 3 is a face view and Fig. 4 a side elevation of a radial stay in which the features of the invention are incorporated.

Fig. 5 is a face view and Fig. 6 a side elevation of one of the sections of the stay.

Fig. 7 is a detail cross-sectional view on the line 7—7 of Fig. 5.

Similar characters of reference designate 110

corresponding parts throughout the several views.

The drawings show a fire-box shell and an outer shell 2 of ordinary construction. The 5 radial stays 3 between these shells are of rod or bolt form and comprise sections 4 and 5 having a flexible jointure with one another and which are secured to the respective shells 1 and 2.

10 According to the present invention, the loose play joint between the stays involves in its articulation a relative outward longitudinal movement of the stay sections while in alining relation and the stay is otherwise constructed, whereby if one of said sections, preferably the upper or outer section, be attached to the shell from which it projects, the other section will, in consequence of the said outward longitudinal movement, 15 pass from a position wherein its remote end is free of the shell to which it is to be subsequently attached to a position wherein said end projects through said shell for the purpose of attachment thereto.

20 25 The loose play joint between the sections 4 and 5 is preferably of the construction which, *per se*, forms the subject of my pending application Serial No. 150,517. Such a joint is shown herein and comprises 30 a pair of counterpart hooks 6, one carried by each section, terminal lugs 7 carried by each hook, and openings 8 in the bows of the hooks through which the lugs 7 project when the hooks are in engaged relation. The legs 35 of each hook are substantially parallel and are suitably spaced to receive between them the outer leg of the companion hook. The length of the hooks is selected to provide for their movement or play longitudinally relatively to one another, and, if desired or necessary, the openings 8 are, as shown, sufficiently wider than the lugs 7 to provide for 40 a certain measure of transverse relative play of the hooks.

45 50 An important advantage of the invention is that it greatly facilitates the use of direct connections between the sections 4 and 5 and the respective shells 1 and 2. By the expression "direct connections" I refer to connections which are rigid or steam-tight, as effected by welding or riveting, and wherein intermediate securing or packing elements, such as nuts or glands, are dispensed with and the removal of the stay sections requires 55 that they shall be merely cut from the shells. While the sections 4 and 5 may be interchangeably secured by welding or riveting, it is preferred to secure the section 4 by welding and the section 5 by riveting. In 60 such a case, the section 5 will first be secured to the shell 2, after which it is articulated with the section 4 and the latter is thereupon secured to the shell 1.

65 As preferred and disclosed, the section 5 is provided with a cylindrical attachment

portion 9 which has threaded engagement in an opening 10 provided therefor in the shell 2; and the said attachment portion is formed externally of said shell, by the tool or implement usually employed for the purpose, with 70 a rivet head 11 which bears against said shell and completes the direct, rigid and steam-tight joint between said shell and the section 5.

The length of the section 4 is selected 75 whereby its lower end will be above the shell 1 during the articulation of said section with the section 5 and while said sections are in alining relation, but will, when said sections have been articulated, project through an 80 opening 13 provided therefor in the shell 1.

It will be observed that the hooks 6 are slightly offset from the respective sections 4 and 5 at relatively opposite sides of said sections and that the neck 12 which connects 85 each hook to its section is relatively wide and heavy and provides a reinforcement for the hook which, as regards strength, compensates for its offset relation. The hooks 6 are offset as described in order that the 90 shanks or body portions of the sections 4 and 5 may be in axial alinement with one another whereby the resisting pull of the stay will be along a straight line or axis common to the sections 4 and 5; and the engaging or 95 co-acting parts of the hooks 6 are so located that they will be in the said common line of axial pull. By virtue of these features, all parts of the stay, including the flexible joint between its sections, possess great strength 100 and efficiency for the contemplated purpose of bracing the shells 1 and 2 relatively to one another.

The offset relation of the hooks 6 in the embodiment disclosed makes it necessary in 105 the articulation of the sections 4 and 5 to first move said sections transversely relatively to one another whereby the outer leg of each hook 6 will enter between the legs of the companion hooks. This transverse 110 movement may be performed with ease and facility even in the narrowest or least accessible parts of the steam space between the shells, and it is continued until the lugs 7 align with the openings 8, after which the 115 section 4 is longitudinally moved outward relatively to the section 5 or toward the shell 1 to cause the lugs to pass through the openings 8. During such longitudinal movement of the section 4, it is held in alinement or 120 substantial alinement with the section 5, this being aided by the engagement of the lugs 7 in the openings 8, and as thus alined or substantially alined with the section 5, the outer or lower end of the section 4 passes through 125 the opening 13 of the shell 1.

As previously stated, the section 4 is preferably secured to the shell 1 by welding. A welded connection between the section 4 and the shell 1 is not only direct, rigid and 130

steam-tight, but it is of further and important advantage in that it greatly resists the destructive effects of the intense heat prevalent under low water conditions and, retaining its integrity under such conditions, in very large measure prevents the rupture or collapse of the fire-box shell.

Where the section 4 is secured to the shell 1 by welding, its lower or outer end has a 10 tapering attachment portion 14 which facilitates its introduction into the opening 13 and provides for a clearance 15 between it and the wall of the opening 12 and enables the welding to be effected with the oxy-acetylene blow-pipe in the well known manner. The increased surface provided by the clearance 15 insures of an extremely efficient welded joint 16 between the section 4 and the shell 1.

20 It will be observed that the openings 10 and 13 conform in diameter to the diameters of the sections 5 and 4 or, stated otherwise, are of the smallest possible diameter. This is an incident of the described direct connections between said sections and the shells and has the advantage of reducing the impairment of the tensile strength of the shells in connection with the attachment of the stays thereto to a minimum.

30 When renewing the shells, the sections 4 or 5, as the case may be, are cut off as close as possible to the surface of the shell to which they are secured. Such cutting of said sections shortens them very slightly, 35 but since it does not affect the flexible joint between them it does not interfere with their further use as elements of radial stays, the only requirement being that as re-used their location must be changed to some point 40 where the radial distance between the shells will be less to the extent that the length of the sections is made less by cutting from them their end portions which project through the openings 13 or 10 of the respective shells. In the renewal of either of the 45 shells those of the sections 4 or 5, according to the shell being renewed, which are elements of the shortest of the radial stays may have new shanks or body lengths 50 welded to them to convert them, in effect, into the new sections 4 or 5 that must be supplied for the longest stays. A very great economy is obviously effected by the re-use of the stays as described.

55 The flexible joints of the stays may be located at any desired point in their length; although it is preferred that their location, *i. e.* distance from one of the shells, shall be the same throughout the boiler and shall be 60 somewhat close to the outer shell in order that they may be for the most part above the water level and, therefore, substantially free from deposits or corrosion. Said joints may also be disposed in any desired planes, 65 although if not interfered with by the

necessary arrangement of other internal parts, they are preferably disposed with their hooks 6 in longitudinal radial planes of the boiler.

The joint disclosed possesses marked advantage in point of flexibility, strength and general adaptability to the environments of its use.

I claim as my invention—

1. A radial stay for the fire-box shell and outer shell of locomotive boilers comprising a pair of rigid sections adapted to be connected to the respective shells and each having an element for its jointure to the other, the said elements being adapted for interlocking engagement by an initial transverse relative movement and by a subsequent relative outward longitudinal movement and when interlockingly engaged having a measure of longitudinal loose play to enable said shells to expand and contract independently of one another.

2. A boiler having a fire-box shell and an outer shell, one of said shells being provided with openings for radial stays in combination with a radial stay comprising a pair of rigid sections adapted for rigid connection to the respective shells and each having an element for its jointure to the other, the said elements being adapted for interlocking engagement by an initial transverse relative movement and by a subsequent relative outward longitudinal movement during which said sections are alined and the end of one of them passes through one of the said openings and means for rigidly securing said end in said opening, said elements when interlockingly engaged having a measure of longitudinal loose play to enable said shells to expand and contract relatively to one another.

3. A boiler having a fire-box shell and an outer shell, and a radial stay comprising a pair of rigid sections adapted for connection to the respective shells and having a flexible jointure with one another which requires for its completion a relative outward longitudinal movement of said sections in alining relation, the length of said sections being such that when one of them is attached to the shell from which it projects the other, positioned for the inception of said longitudinal movement and alined with the first section, will have its end located free of the shell to which it is subsequently connected, and upon the completion of said longitudinal movement will have said end inserted through said shell.

4. In a boiler having a fire-box shell and an outer shell, a radial stay comprising a pair of sections adapted for connection to the respective shells and having a flexible jointure with one another, said sections for such jointure being provided with companion hooks adapted for relative longitudinal

movement when in engaged relation, the length of said sections being such that when one of them is attached to the shell from which it projects the other with its hook engaged with the hook of the first section and being in alinement with the first section, may be moved longitudinally outward relatively thereto from a position wherein its end is free of the shell to which it is subsequently attached to a position wherein said end projects through said shell.

5. In a boiler having a fire-box shell and an outer shell, a radial stay comprising a pair of sections adapted for connection to the respective shells and having a flexible jointure with one another, said sections for such jointure being provided with companion hooks offset at relatively opposite sides of the respective sections and adapted for 10 articulation by an inward relative transverse movement and a subsequent relative outward longitudinal movement, the length of said sections being such that when one of them is attached to the shell from which it projects, 15 the other with its hook engaged with the hook of the first section, and being in alinement with the first section, may be moved longitudinally outward relatively thereto from a position wherein its end is free of the shell to which it is subsequently attached to a position wherein said end projects through said shell.

6. A boiler having a fire-box shell and an outer shell, and a radial stay comprising a 20 pair of rigid sections adapted for rigid connection to the respective shells and having a flexible jointure with one another which requires for its completion a relative outward longitudinal movement of said sections in 25 alining relation, the length of said sections being such that when one of them is attached to the shell from which it projects, the other positioned for the inception of 30 said longitudinal movement and alined with the first section, will have its end located 35

free of the shell to which it is subsequently connected, and upon the completion of said longitudinal movement will have said end inserted through said shell, said last-named section having its said end of tapering outline for co-action with an opening therefor in the shell to which it is to be attached to provide a welding clearance between it and said opening.

5. A radial stay for the fire-box shell and outer shell of locomotive boilers comprising a pair of sections adapted to be connected to the respective shells and a flexible joint between the sections comprising hooks carried by said sections and offset at relatively opposite sides thereof whereby the body portions of the sections will be in alinement with one another, each hook having an inner and an outer leg, the outer leg of each hook fitting between the legs of the companion hook and the engaging mutually co-acting parts of said hooks being in the line of pull of said sections.

7. A boiler having an outer shell and a fire-box shell, the latter having openings for the ends of radial stays, a radial stay having rigid sections for rigid attachment to the respective shells and a flexible joint between said sections requiring for its articulation a relative outward longitudinal movement 75 thereof, the inner end of the section for attachment to the fire-box shell being inserted through an opening therefor in said fire-box shell when said section is moved longitudinally outward relative to the other section 80 and a welded joint between said inserted end and said fire-box shell.

In testimony whereof I have hereunto set my hand in presence of two subscribing witnesses.

ALLAN R. HODGES.
